MEANS FOR PRODUCING REDUPLICATIVE
MASTER SHEETS IN TYPEWRITING AND
LIKE MACHINESClaude Wellington Brumhill, Leicester, England,
assignor to The Imperial Typewriter Company
Limited, Leicester, EnglandApplication October 24, 1945; Serial No. 624,160
In Great Britain June 7, 1945

3 Claims. (Cl. 197—153)

1

This invention concerns typewriting and like machines of the kind (commonly known as hectograph machines) wherein the type impressions are produced in reverse on the back of a master sheet, of paper or the like, by feeding a ribbon at the typing station between said sheet and a support surface such as a platen. This master sheet is subsequently employed for the production of a multiplicity of copies of the master sheet by a hectograph duplicating process.

In order to get clear and legible copies from the master sheet it is desirable that the sheet be typed on a platen with a reasonably hard surface but not so hard that the master sheet and the hectograph ribbon are liable to be perforated by the impact of the type heads. It so happens that although rubber faced platens are known which initially give satisfactory results, after a time the surface hardens up and the results deteriorate. Moreover, at the present time, owing to the scarcity of rubber, platens having a facing of cork are in general use and owing to their granular surface these platens give poor results. An object of the present invention is to overcome these difficulties and to provide means whereby good impressions may be obtained substantially irrespective of the quality of the platen itself.

Therefore, the invention provides in a typewriting or like machine of the kind specified, a thin anvil at the typing station for location between the ribbon and support surface, to take the typing impacts. Such an anvil may readily be produced having the desired combination of hardness and a certain degree of resilience, and although if as preferred the anvil has a stationary location the typing impacts will appear in succession on the same area of it matters may readily be so arranged that the anvil is readily detachable from a support so that a used anvil may be replaced by a new one. This support advantageously extends forwards and downwards.

The anvil is preferably made of a slightly resilient non-metallic sheet material such for example as waxed paper, Celluloid and certain other synthetic resins.

The foregoing and other features of the invention set out in the appended claims are incorporated in the construction which will now be described with reference to the accompanying drawings, in which—

Figure 1 is a plan of a typewriter of the kind specified;

Figure 2 is a front elevation of the platen, the ribbon guide heretofore mentioned and the anvil;

2

Figure 3 is a section on a larger scale taken on the line J—J in Fig. 2;

Figure 4 is a front elevation of the anvil, and Figure 5, an end elevation thereof.

The invention is shown as applied to a typewriter having a body 1 with a keyboard 2 incorporating a tabulating key 3, a carriage (indicated generally at 4) incorporating a platen 6 with line space lever 8, feed rolls 9 for feeding the master sheet 10 round the platen, means for feeding a normal typewriter ribbon 11 in front of the master sheet 10 at typing station TS so as to be struck by the type heads 12, and means for feeding hectograph paper ribbon 13 along the face of the platen at the back of the master sheet 10 with its treated face forward.

A stationary support arm 16 curves forwards and downwards over the carriage 4 and supports at the typing station a stationary ribbon guide 14 for engaging and positioning the ribbon 13 at the back of the sheet 10. This guide forms the subject of co-pending U. S. patent application Serial No. 624,159 and it comprises legs 15 spaced apart one at each side of the typing station which have upper and lower lobes 15a and 15b respectively for embracing the edges of the ribbon 13 and for positioning the latter against edgewise displacement. It will be seen that the arm 16 affords room beneath it at the rear of the platen 6 to accommodate the sheet 10 which is to be fed under the platen, and that its front end has such a location that the sheet 10 in ascending from the typing station passes up in front of it.

The anvil 25 is detachably mounted on this guide 14 to form a backing strip which is interposed between the ribbon 13 and the face of the platen 6 at the point between the guide legs 15 whereat the type impacts occur. It therefore relieves the surface of the platen of these impacts. Its shape is best disclosed in Figs. 4 and 5 from which it will be seen that it is curved to conform to the curvature of the platen and has a top bar 25a which serves for its attachment to the guide 14 and a central depending leg 25b which hangs between the guide legs 15 and the surface of which takes the typing impact. It is detachably mounted by means of dome headed studs 26 on guide 14 which enter openings 27 in the top bar 25a.

It will therefore be appreciated that this stationary removable backing strip 25 permits a good impression to be obtained on the master sheet 10 (resulting in clear duplicates of the master sheet) substantially irrespective of quality of surface of the platen.

The anvil is cheap to produce and after one of them has been in use for a period a new one may readily be substituted for it when it becomes worn.

I claim:

1. In a typewriting machine of the kind in which type impressions are produced in reverse on the back of a master sheet, by feeding a ribbon between the sheet and the front of a rotary platen with an impression-producing face of the ribbon presented to the back of said sheet at a typing station at the front of the platen, the combination with the rotary platen, means for feeding the master sheet down under the platen from the back and up the front thereof past the typing station, and ribbon-feeding means for feeding the ribbon between said sheet and platen at the typing station, of a thin anvil of sheet material for taking the type impacts at the typing station, and means for supporting said anvil at said station between the ribbon and the front of the platen which means comprises a stationary anvil-support arm extending forwards from the rear of the machine and at its front end leading downwards over the platen there to be located behind the sheet ascending from the typing station and affording room beneath it at the rear of the platen for accommodating the sheet to be fed under the platen, and means on the front end of said arm for the removable attachment of the anvil.

2. In a machine according to claim 1, the combination of means for feeding the ribbon lengthwise of the platen, a ribbon guide on said arm which guide comprises means for engaging top and bottom margins of the ribbon at both sides of the typing station, and means for mounting the anvil between said ribbon engaging means.

3. In a typewriting machine of the kind wherein type impressions are produced in reverse on the back of a master sheet by feeding a ribbon at a typing station behind said sheet and between it and a rotary platen which traverse endwise, the combination with type for producing the impressions, ribbon feeding means for feeding the ribbon along the front of the platen lengthwise of the direction of traverse, means for feeding the sheet upwards past the front of the platen and from the typing station, a stationary support member extending forwards from the rear of the machine and at its front end leading down over the platen towards the typing station there to be located behind the sheet ascending from the platen and affording room beneath it at the rear of the platen for accommodating the sheet to be fed under the platen, and a ribbon guide on the support member for engaging the ribbon behind the sheet and in the region of the typing station and for positioning the ribbon against upward displacement; of a thin anvil, for taking the type impacts at the typing station, carried by the support member and positioned thereby at the typing station between the ribbon and the face of the platen.

CLAUDE WELLINGTON BRUMHILL.
